PORTABLE FLUORESCENT LAMP OR SIMILAR ARTICLE

Howard W. Phillips, Nashville, Tenn., assignor to Aladdin Industries, Incorporated, Chicago, Ill., a corporation of Illinois

Filed May 18, 1965, Ser. No. 85,343

Term of patent 14 years

(Cl. D48—24)

FIG. 1

FIG. 1 is a perspective view of the front, top and left side of a portable fluorescent lamp or similar article showing the new design;

FIG. 2 is a perspective view of the rear, bottom and right side thereof; and

FIG. 3 is a left side elevational view thereof with the handle in a changed position.

The diagonal surface shading on the lens element indicates translucency. The lower quadrant of the lamp face is lined to indicate color contrast.

I claim:

The ornamental design for a portable fluorescent lamp or similar article, as shown and described.
